CUFF FOR TROUSERS

Application filed May 28, 1930. Serial No. 456,711.

This invention relates to apparel and more particularly to trousers of the type in which cuffs are formed at the lower ends of the trousers legs.

5 At the present time it is customary to form cuffs at the lower ends of trousers legs in order to improve the appearance of the trousers. In some cases the cuffs are merely formed by turning up the lower portion of the trousers 10 legs and pressing them to form a cuff and in other cases the cuffs are stitched at their upper edges at spaced intervals circumferentially of the trousers legs in order to retain the cuff in its proper position. It has been found that 15 dust collects in the cuff and if a person is walking through sand or across very dry soil, sand and fine dirt will accumulate in the cuff. It is sometimes difficult to remove the dirt and 20 dust from the cuff, and, therefore, one object 25 of the invention is to provide an improved type of cuff having outlet openings formed in its inner wall through which dust, sand or dirt may easily pass if it enters the cuff and thereby prevent it from accumulating in the

Another object of the invention is to so form the outlet openings that when the lower portion of a trousers leg is folded upwardly to form a cuff the openings will be disposed in 30 the inner wall of the cuff above the fold line and thereby prevent the openings from showing and also prevent the lower edge of the trousers leg from having a ragged appearance.

35 Another object of the invention is to provide the cuffs with outlet openings of such shape that the dust and dirt will be permitted to pass freely through them out of the cuff and also to so bind the margins of the 40 openings that fraying about the openings will be prevented.

The invention is illustrated in the accompanying drawings, wherein

Figure 1 is a perspective view of a pair of 45 trousers having cuffs formed with outlet openings in accordance with this invention.

Fig. 2 is an enlarged fragmentary sectional view taken on the line 2—2 of Fig. 1,

Fig. 3 is a fragmentary perspective view 50 looking at the inner face of a trousers leg and

are formed, and
Fig. 4 is a view showing the manner in which the leg of a pair of trousers is cut to form the outlet openings.

The trousers, indicated in general by the numeral 1, are in most respects of a conventional construction and have the usual body portion 2 and legs 3. The lower portion of each leg is to be turned upwardly in order to form a cuff 4 having an outer wall 5 and inner wall 6 and the outer wall may be left free at its upper edge or it may be stitched at spaced intervals about the circumference of the trousers leg. Before the lower ends of the trousers legs are folded upwardly to form the cuffs, each leg is cut in spaced relation to its lower edge to form openings 7 which are spaced from each other circumferentially of the leg and these openings are so cut that they are arranged in groups at opposite sides of the creases 8 formed at the front and back of the trousers when they are pressed. The lower edge of each opening extends in a straight line circumferentially of the trousers and the upper edges of the openings are arcuate so that the openings taper upwardly. After the openings have been cut their margins are bound by buttonhole stitching, as shown at 9, in order to prevent fraying. It should be noted that these openings are so located that when the lower end portion of the leg is turned upwardly to form the cuff the openings will be located in the inner wall of the cuff with their straight cut lower edges coincident with the lower edge of the cuff. Therefore, 50 openings will be formed in the bottom of the cuff through which dust, sand or other dirt may easily pass. By this arrangement dust and dirt will be prevented from collecting in the cuffs.

Having thus described the invention, I claim:

1. Trousers having lower ends of the legs formed with cuffs, openings being formed in the inner wall of each cuff in spaced relation to each other and each having a straight lower edge substantially coincident with the lower edge of the cuff.

2. Trousers having lower ends of the legs formed with cuffs, openings being formed in the inner wall of each cuff in spaced relation to each other along the lower edge of the cuff.
5. Trousers having lower ends of the legs formed with cuffs openings being formed in the inner wall of each cuff in spaced relation to each other, each opening having a straight lower edge coincident with the lower edge of the cuff and being tapered upwardly.
10. Trousers having lower ends of the legs folded outwardly and upwardly to form cuffs having inner and outer walls, each trousers leg having openings cut therein in spaced relation to each other circumferentially of the leg above the fold line and disposed in the inner wall of its cuff and serving as outlets for dust and dirt deposited in the cuff.
15. Trousers having lower ends of the legs folded outwardly and upwardly to form cuffs having inner and outer walls, each trousers leg having openings cut therein in spaced relation to each other circumferentially of the leg above the fold line and disposed in the inner wall of its cuff and serving as outlets for dust and dirt deposited in the cuff.
20. Trousers having lower ends of the legs folded outwardly and upwardly to form cuffs having inner and outer walls, each trousers leg having openings cut therein in spaced relation to each other at opposite sides of front and rear creases of the trousers, the openings being located above the fold line constituting the lower edge of the cuff and disposed in the inner wall of the cuff, and stitching forming a finish for margins of each opening.
25. Trousers having lower ends of the legs folded outwardly and upwardly to form cuffs having inner and outer walls, each trousers leg having openings cut therein in spaced relation to each other at opposite sides of front and rear creases of the trousers, the openings being located above the fold line constituting the lower edge of the cuff and disposed in the inner wall of the cuff, and stitching forming a finish for margins of each opening.
30. Trousers having lower ends of the legs folded outwardly and upwardly to form cuffs having inner and outer walls, each trousers leg having openings cut therein in spaced relation to each other at opposite sides of front and rear creases of the trousers, the openings being located above the fold line constituting the lower edge of the cuff and disposed in the inner wall of the cuff, and stitching forming a finish for margins of each opening.

In testimony whereof I affix my signature.
